United States Patent Office.

J. THOMPSON CREE, OF WORCESTER, MASSACHUSETTS.

Letters Patent No. 90,822, dated June 1, 1869.

IMPROVED STONE-DRESSING MACHINE.

The Schedule referred to in these Letters Patent and making part of the same.

Know all men by these presents:

That I, J. THOMPSON CREE, of the city and county of Worcester, and Commonwealth of Massachusetts, have invented certain new and useful Improvements in Stone-Dressing Machines, of which the following is a full, clear, and exact description, reference being had to the accompanying drawings, forming a part of this specification, in which—

Figure 1 represents a side view of my improved stone-dressing machine;

Figure 2 represents a top, or plan view of the same;

Figure 3 represents a section on line A B, fig. 1;

Figure 4 represents, upon an enlarged scale, pieces of broken buhrstone, used in the process of dressing stone by my machine; and

Figure 5 represents, upon an enlarged scale, pieces of chilled iron, used in the same manner.

To enable those skilled in the art to which my invention belongs, to make and use the same, I will describe it more in detail.

The nature of my invention consists—

First, in the combination with the base, or bottom of the frame, which supports the lower stone, of a series of friction-balls, as will be hereafter explained.

Second, in the combination with the frame, which supports the lower stone, of a series of friction-balls and two operating cranks, or eccentrics, as and for the purposes hereafter explained.

Third, in the combination with the frame which supports the upper stones, of a series of friction-balls, as hereafter set forth.

Fourth, in the combination with the upper and lower stone-frames, of the supporting and operating-mechanism, or devices.

Fifth, in the combination with the blocks of stones to be polished, arranged in reciprocating frames, as hereafter described, of small pieces of buhrstone, chilled iron, and steel, as hereafter explained.

In the drawings—

A is the base of the machine, upon which are secured four upright stands, or columns B B B B, one at each corner. The tops of the columns, or stands B are, in this instance, enlarged, as shown at a, the upper face of the columns being recessed, or cored out to form chambers, or concavities, shown in dotted lines, to receive the friction-balls b, one to each column, for supporting the metal box-frame C, which is provided upon its under side with projections c, one at each corner, said projections c being recessed or cored out upon their lower sides to form recesses, shown in dotted lines, to receive the friction-balls b, as indicated in the drawings.

It will be seen that the lower stone-frame C is supported upon four friction-balls b, one at each corner, and that the recesses, or chambers in the under side of the projections c, and in the tops of the columns B,

in which the friction-balls b work, are of sufficient size to allow of a forward, back, and lateral motion to said frame, to conform to the motion of two cranks, or eccentrics d, one at each end of said frame, said cranks being connected to vertical shafts e, having bevel-gears f on their lower ends, which mesh into and receive motion from the bevel-gears g, on the horizontal shaft D, the upright crank-shaft being supported in proper frames E, one of which is shown in fig. 3.

The crank-pins h fit into holes in projections j, upon the under side of the stone-frame C, one of the crank-shafts d being arranged at each end of the frame and between the columns, or stands B B, at that end.

Outside of the columns B are four upright screw-shafts, or standards F, provided with supporting-nuts m, upon which rests the frame G, the upper ends of the screw-shaft F passing through ears, or projections n of said frame, and being, in this instance, fitted with clamp-nuts o.

Grooved flanges p project in from the inner sides of frame G, in which are arranged friction-balls 1, for supporting the upper stone-frame H, which is provided with outward projecting flanges 2, the under sides of which are grooved out to fit the friction-balls 1, as indicated in fig. 3.

The front of frame G is connected to the upright crank-shaft I by means of connecting-rod J, the lower end of crank-shaft I being provided with a bevel-gear, 3, which meshes into bevel-gear 4, on the end of the horizontal shaft D.

The mode of operation is as follows:

A block of stone, K, to be dressed, is arranged in the box-frame C, and adjusted in a proper position by the set screws 5, and clamping-piece 6. Two other blocks of stone L L are arranged in the upper stone-frame H, which are also adjusted in position by means of the clamping-screws 7 and clamping-pieces 8, said blocks being separated by means of pieces 9, so as to leave an opening, s, between them, as indicated in figs. 2 and 3.

Frame G is now adjusted, by means of nuts m, to support the stone-frame H and blocks of stone L L, at the desired and proper height above the stone K. Motion is now imparted to shaft D in any suitable manner, whereby a rotary reciprocating motion is communicated, through the cranks d d, to the lower stone-frame C, while a reciprocating motion is imparted, through crank-shaft I and connecting-rod J, to the upper stone-frame H.

If the faces of the stones to be dressed are rough and uneven, the attendant shovels into the opening s small pieces of broken buhrstone, or small pieces of chilled iron mixed with water, which, passing down between the blocks of stone L L, are drawn in between the lower faces of said stones and the upper face of block K, and by the rotary reciprocating motion of

the latter, and the reciprocating motion of blocks L L, the lower faces of the latter and the upper face of the former are rapidly cut away by the pieces of chilled iron, or broken pieces of bulhrstone.

After the faces of the blocks have been reduced to even and uniform surfaces, the upper blocks can be lowered by turning screws *m*, so as to bring the rubbing-faces of the stones sufficiently near to each other to commence the polishing-operation, which may be accomplished by the attendant introducing through the opening *s* sand and water, or punice-stone.

To facilitate the dressing and polishing-operation, a box, or receptacle, *M*, is arranged at one side of the machine, which box is divided into compartments, as indicated in fig. 2, for containing the pieces of chilled iron, broken pieces of bulhrstone, and sand, and from which they can be conveniently shovelled by the attendant into the opening *s*, while the machine is in operation.

Instead of the flanges 2 running on friction-balls, they may be arranged or fitted to work in grooves, or ways upon the insides of the frame *G*, and nuts *m* may be combined with bevel-gears and shafting, whereby they can all be moved up and down by turning a single shaft or crank, and nuts *o* may be dispensed with in some cases, the frame and weight of the stones being quite sufficient to retain the upper frame in position.

By supporting the lower frame and stone upon friction-balls, as shown and described, it requires but little power, comparatively speaking, to operate the machine, to what it would if said frame run on stationary ways, or guides.

The upper frame *H* can rise slightly, in case of clogging, thereby insuring free working of the machine, which is thus rendered self-clearing.

It will be observed that the sides of the frames *H* and *C* always work in lines parallel with each other, although the latter is moved back and forth laterally, while it has a reciprocating motion longitudinally, the same as frame *H*.

An apron may be attached to the lower part of frame *C*, of such size as to prevent any water or dirt from falling into the chambers, or recesses in which the friction-balls *b* work, and, if found necessary, a similar apron may be attached to the upper frame.

In lieu of a single or large block of stone being

placed in the frame *C*, several smaller blocks may be arranged therein at the same time.

By the arrangement of two separate upper blocks, and the use of broken pieces of bulhrstone, or pieces of chilled iron or steel, as described, a far greater amount of work can be turned out by a single machine than could be accomplished by the machine if it depended upon the simple friction, or rubbing of the upper stone upon the lower one.

Oil may be turned into the recesses, or concavities in which the friction-balls *b* work, to lessen their friction as they roll from side to side.

Having described my improved stone-dressing machine,

What I claim therein as new, and of my invention, and desire to secure by Letters Patent, is—

1. The frame *C*, supported upon friction-balls, substantially as and for the purposes set forth.

2. The combination, with the columns, or standards *B*, and frame *C*, of the friction-balls *b*, substantially as and for the purposes set forth.

3. The combination, with the frame *C*, supported upon friction-balls, of the operating-crank *d d*, substantially as described.

4. The combination, with a lower stone-frame, having a rotary reciprocating motion, of an upper stone-frame, having a reciprocating motion, substantially as described.

5. The combination, with frames *G* and *H*, of the friction-balls *l*, substantially as and for the purposes set forth.

6. The arrangement with the upper reciprocating frame *H*, of two blocks of stone, to be ground and polished, substantially as shown and described, whereby a central longitudinal opening, *s*, is left between them for the reception and more rapid and even distribution of the grinding and polishing-material, substantially as described.

7. The combination, with the blocks of stone to be ground and polished, arranged in reciprocating-frames, the upper one of which is capable of rising, for the purpose stated, of small pieces of bulhrstone, chilled iron, and steel, substantially as and for the purposes set forth.
